UNITED STATES PATENT OFFICE.

WILLIAM J. EMBS, OF IRON RIVER, MICHIGAN.

FUEL-FEEDING DEVICE.

1,305,648.

Specification of Letters Patent. Patented June 3, 1919.

Application filed July 23, 1918. Serial No. 246,320.

To all whom it may concern:

Be it known that I, WILLIAM J. EMBS, a citizen of the United States, residing at Iron River, in the county of Iron and State of Michigan, have invented certain new and useful Improvements in Fuel-Feeding Devices, of which the following is a specification.

This invention relates to improvements in fuel feeding devices for liquid fuel burners and it is the principal object of the invention to provide a novel form of reservoir fuel feeding device particularly adapted for use in connection with oil burner stoves of the lamp type, whereby the reservoir thereof can be easily and quickly filled with oil without inverting the same as is necessary with the prevalent forms of similar devices at the present day.

Another and equally important object of the invention is to provide the device with novel vent means whereby the air is allowed to escape from the reservoir when reservoir is being filled through a tube opening into the bottom of same.

Other objects will be in part obvious and in part pointed out hereinafter.

The improvements in the details and arrangement of parts will be apparent from an inspection of the accompanying drawings when considered in connection with the specific description hereinafter contained and wherein a preferred embodiment of the invention is disclosed for the purpose of imparting a full understanding thereof.

In the drawings:

Figure 1 is a vertical longitudinal section through the improved device.

Fig. 2 is an end elevation thereof, and

Fig. 3 is a horizontal section through the same.

Referring to the drawings, *r* represents the reservoir of the improved fuel feeding device, and *c* the ordinary form of oil cup or receiving receptacle, which as will be noted, is arranged therebeneath and has communication with the burner proper of the stove, not shown by way of a conduit *c'*.

Formed in the bottom of the reservoir *r* is an outlet opening having a neck 1 extending therefrom, the lower portion of which is constricted as at 2 to form an effectual valve seat, to receive a conical valve 3 therein, said valve having its upper portion engaged by one end of a coil spring 4, the remaining end of which, as will be noted, bears upon a cross pin 5 positioned adjacent the outlet

opening. The valve 3 may be and preferably is provided with an elongated stem portion 6 adapted to be engaged, at times, with the bottom of the oil cup *c* whereby to effect the unseating of said valve and the resultant flow of fuel from the reservoir *r* into the cup *c*.

Extending from the bottom of the reservoir *r* is a vent pipe 7, it being noted that the upper end of said pipe is extended to a point in proximity to the closed top of the reservoir and, obviously, serves to permit the escape of air from the reservoir when the reservoir is raised and is being filled.

A filling tube 8 is arranged adjacent one end wall of the reservoir *r* and has its lower end curved upon itself as at 9 and extended through an opening formed in the adjacent portion of the reservoir bottom; the upper or remaining end of the filling tube being beveled as at 10, for a purpose which will be presently described. As will be understood, it will be noted the curved end 9 of the tube 8 is arranged at a point below the level of the fuel in the cup *c*. In this connection, it may be noted that a portion of the oil cup *c* is recessed as at 11 to permit the passing of the curved lower end 9 of the filling tube 8 thereby.

As means for moving the reservoir *r* vertically with relation to the oil cup *c*, standards 12 are engaged with a portion of the frame of the oil stove, not shown, and, as shown in Fig. 1, certain of the same are pivotally engaged with the bell crank shaped extremities of a substantially U-shaped lever 13, said extremities being pivoted to the reservoir *r* at 13', while the remaining standards are pivotally engaged by links 14 having pivotal connection at 15 with the reservoir *r*. In this way, it is obvious that when the lever 13 is moved downwardly to the position shown in dot and dash lines in the Fig. 1, the reservoir *r* will be moved upwardly from the cup *c*, thus allowing the conical valve 3 to be seated on the constricted portion 2 of the outlet neck 1 and in this way prevent the flow of oil from the reservoir into the cup. It is to be further noted, that when the lever 13 is in its uppermost position, as shown in dotted lines in the Fig. 1, the lateral portion thereof is engaged over the beveled upper end of the filling tube 8, thus forming an effectual closure therefor, while the positioning of the bell crank shaped extremities thereof and the links 14 is such as to effect the lowering of the reser-

voir *r* into engagement with the oil cup *c*. By reason of such engagement of the reservoir with the oil cup, the extended stem 6 of the valve 3 will engage the bottom of the 5 oil cup and consequently, will move said valve 3 upwardly from the constricted portion 2 of the neck 1, hence, permitting liquid fuel to flow therefrom into the cup. As the level of the liquid fuel in the cup *c* reaches 10 the lower end of the vent pipe 7 and the constricted portion 2 of the outlet neck 1, the same will be closed and the flow of air upwardly therethrough into the reservoir *r* will be discontinued. Consequently, the flow 15 of liquid fuel from the reservoir will be interrupted. However, as the fuel is exhausted from the cup *c* and the level thereof again falls below the adjacent end of the vent pipe 7, a further supply of fuel will be discharged 20 from the reservoir into the cup.

As it becomes necessary to fill the reservoir *r*, it is only necessary to move the lever 13 downwardly to the position shown in dot and dash lines, whereupon the conical valve 25 3 will be caused to seat in the constricted portion 2 of the neck 1, the constricted portion 2 and the lower end of vent pipe 7 will be raised above the surface of the liquid fuel in oil cup *c*, the liquid fuel in vent pipe 30 7 will drop into cup *c*, while the lateral portion of lever 13 will be disengaged from over the upper end of the filling tube 8, thus allowing the spout or nozzle of the dispensing can to be placed therein. As the 35 liquid fuel is poured into filling tube 8, it will pass up into reservoir *r*, and the air in reservoir *r* will be forced out through vent pipe 7.

Manifestly, the construction shown is 40 capable of considerable modification and such modification as is within the scope of my claims, I consider within the spirit of my invention.

I claim:

45 1. In a fuel feeding device, a movable reservoir having outlet means in its bottom, a receiving receptacle arranged beneath said reservoir, valve means in the outlet operable upon movement of the reservoir 50 with relation to said receptacle, a vent pipe extending from the reservoir to a point adjacent the outlet means, a filling tube arranged adjacent one end wall of said reservoir and communicating with the bottom thereof, standards arranged adjacent the reservoir, a substantially U-shaped lever having the extremities thereof formed at substantially right angles thereto pivoted to the upper ends of certain of said standards, 55 and links pivoted at certain of their ends in the remaining standards and to the reservoir.

60 2. In a fuel feeding device, a movable res-

ervoir having outlet means in its bottom, a receiving receptacle arranged beneath said 65 reservoir, valve means in the outlet operable upon movement of the reservoir with relation to said receptacle, a vent pipe extending from the bottom of the reservoir to a point adjacent the lower end of the outlet 70 means, the upper end of said vent pipe extending to a point in proximity to the closed end of the reservoir, a filling tube positioned adjacent one end wall of the reservoir, and communicating with the bottom thereof, 75 standards arranged adjacent the reservoir, a substantially U-shaped lever having its opposite extremities disposed at right angles thereto pivoted to certain of said standards and to the reservoir, and links pivoted to 80 the remaining standards and said reservoir.

3. In a fuel feeding device, a movable reservoir having outlet means in its bottom, a receiving receptacle arranged beneath said reservoir, a vent pipe extending from the bottom thereof into the receiving receptacle, a filling tube arranged adjacent one end wall of the reservoir and communicating with the bottom thereof, the upper end of the filling tube being beveled, standards arranged adjacent the reservoir, a substantially U-shaped lever having its opposite ends disposed at substantially right angles thereto pivoted to certain of the standards and to the reservoir, the lateral portion of said 90 lever being engageable over the beveled end of the filling tube, at times, and links pivoted to the upper ends of the remaining standards and to said reservoir.

4. In a fuel feeding device, a movable reservoir having an outlet neck extending from the bottom thereof and constricted to form a valve seat, a receiving receptacle arranged beneath said reservoir, a valve arranged in said outlet neck having an elongated stem 105 engageable with the bottom of the receiving receptacle, at times, a vent pipe extending from the bottom of the reservoir to a point adjacent the outlet neck, a filling tube arranged adjacent one end wall of the reservoir and communicating with the bottom thereof, the upper end of said filling tube being beveled, standards positioned adjacent the reservoir, a substantially U-shaped lever having its opposite ends disposed at 110 substantially right angles thereto pivoted to the upper ends of certain of the standards and to the reservoir, the lateral portion of said lever being engageable over the beveled upper end of the filling tube, at 115 times, and links pivoted to the upper ends of the remaining standards and to said reservoir.

In testimony whereof, I affix my signature hereto.

WILLIAM J. EMBS.
